LIQUID COOLED METALLIC BEER KEG

Earl E. Brand, Berlin, N. J.

Application October 24, 1945, Serial No. 624,315

9 Claims. (Cl. 257—15)

1

This invention relates to liquid containers and more particularly to a liquid cooled metallic keg especially designed for transporting and dispensing beer and similar beverages.

This application is a substitute for applicant's prior application, Serial No. 318,185, filed February 9, 1940, now abandoned.

The object of the invention is to provide a beer keg of strong, compact and durable construction in which a cooling medium is caused to circulate vertically around the keg and transversely through the contents thereof so as to keep the beer cool and palatable at all times.

A further object of the invention is to provide a beer keg including inner and outer receptacles spaced apart to form an intermediate cooling compartment and lateral fins or partitions carried by the inner receptacle and engaging the outer receptacle for separating the receptacles and reinforcing the same.

A further object is to provide a liquid cooled beer keg, the outer receptacle of which is provided with inlet and outlet pipes having diverging terminals for directing the cooling fluid on opposite sides of the adjacent partition, there being auxiliary cooling tubes or pipes extending transversely through the inner receptacle and communicating with the intermediate compartment for permitting the flow of cooling fluid through the beer or other contents of said inner receptacle.

A further object is to provide the opposite ends of the transverse cooling tubes with terminal troughs for catching and directing the initial flow of cooling fluid through said tubes, means being provided at one end of the keg for connecting said keg with a suitable dispensing apparatus.

A still further object of the invention is generally to improve this class of devices so as to increase their utility, durability and efficiency as well as to reduce the cost of manufacture.

In the accompanying drawings forming a part of this specification and in which similar numerals of reference indicate corresponding parts in all the figures of the drawings:

Figure 1 is a perspective view of a liquid cooled metallic beer keg constructed in accordance with the present invention.

Figure 2 is a similar view with the upper half of the outer barrel or receptacle removed to show the construction of the inner receptacle.

Figure 3 is an enlarged vertical sectional view taken on the line 3—3 of Figure 1.

Figure 4 is a transverse sectional view taken on the line 4—4 of Figure 3.

2

Figure 5 is a bottom plan view of the inner barrel or receptacle.

Figure 6 is a detail sectional view taken on the line 6—6 of Figure 3, and

5 Figure 7 is a perspective view of one of the cooling tubes detached showing one end of the tube split preparatory to forming a terminal trough and the other end thereof with the metal bent laterally at the split portion thereof to form 10 a trough.

The improved liquid cooled beer keg forming the subject-matter of the present invention comprises an inner metallic barrel or receptacle 5 and an outer barrel or receptacle 6 spaced apart 15 to form an intermediate compartment 7 adapted to receive a suitable liquid cooling medium for keeping the beer in the inner receptacle cool and palatable at all times.

The outer barrel or receptacle 6 is preferably 20 formed in two sections, the adjacent ends of which are welded or otherwise suitably united, as indicated at 8. Extending laterally from the intermediate portion of the inner receptacle 5 is a short pipe section or bung 9 through which beer is introduced within said inner receptacle when filling the keg, said bung extending through registered recesses 10 formed in the sections of the outer receptacle and having its outer end provided with a suitable plug or closure 11. Extending laterally 25 from the inner receptacle 6 and secured thereto in any suitable manner is a circumferential fin or partition 12 which extends transversely across the top 13 and bottom 14 of the inner receptacle and vertically of the sides thereof. Intersecting the 30 fin or partition 12 is a second fin or partition 15 which extends across the top of the inner receptacle and downwardly along the outer sides thereof and terminates flush with the bottom 14, as indicated at 16, so as not to interfere with the 35 circulation of cooling fluid around and beneath the inner receptacle. The outer edges of the fins 12 and 15 bear against the inner wall of the outer receptacle 6 and thereby not only direct the flow 40 of cooling medium around the inner receptacle but by engagement with the inner wall of the outer receptacle serve to reinforce and strengthen 45 both receptacles and prevent denting or battering of the key when subjected to rough usage.

Extending through a chime 17 at the top of the outer barrel or receptacle is an inclined liquid conducting inlet pipe 18 provided with diverging branch pipes or terminals 19 which span the adjacent fin or partition 12 and serve to direct the cooling medium downwardly on opposite sides 50 of the fin and beneath the bottom of the inner

receptacle and thence upwardly to a discharge pipe 20 extending through said chime at a point diametrically opposite the inlet pipe 18, as best shown in Figure 3 of the drawings. The outlet pipe 20 is likewise provided with diverging branch pipes or terminals 21 which span the fin 12 so as to receive the cooling liquid on each side of said fin 12 and discharge the same through the outlet pipe 20 after said cooling fluid has circulated within the intermediate compartment and around the inner receptacle or barrel. Depending from the bottom of the inner receptacle 14 are lugs or feet 22 which serve to support the weight of the inner receptacle and also space the bottom of the inner receptacle from the bottom of the outer receptacle.

Extending transversely through the inner receptacle 5 are a plurality of cooling tubes 23, the outer ends of which communicate with the intermediate liquid receiving compartment 7 so as to permit the free circulation of cooling medium transversely through the beer or other contents of said inner receptacle. The metal at the opposite ends of the cooling tubes 23 is formed with intersecting transverse and longitudinal incisions 24 and 25 and the metal at said incisions is bent laterally to form terminal troughs 26. The inner edges of the troughs 26 bear against the outer wall of the inner receptacle 5 so as to lock the tubes against accidental displacement while the outer edges of the troughs 26 bear against the inner wall of the outer receptacle 6 and thereby assist in spacing the inner and outer receptacles and at the same time tending to reinforce the same. The purpose of the troughs 26 is to intercept and direct the initial flow of cooling medium through the tubes 23 so as to effect instantaneous cooling of the beer within the inner receptacle, it being understood that after the inner compartment 6 has been entirely filled with cooling fluid, said fluid will circulate freely through the tubes 23 as well as around the inner receptacle and thus maintain the beer in said inner receptacle in a cool palatable state at all times.

Disposed at the intersection of the fins or partitions 12 and 15 and communicating with the interior of the inner receptacle or barrel 5 is a short pipe section or tube 27 for connection with a standard beer dispensing apparatus. The tube or pipe section 27 is normally closed by a cap 28 and similar caps 29 form closures for the inlet and discharge pipes 18 and 20, respectively.

In operation, the inner barrel or receptacle 5 is filled with beer through the bung 9, after which the closure 11 is positioned within the bung and the caps fitted over the tube 27 and inlet and discharge pipes 18 and 20. When a keg of beer is delivered at a saloon, restaurant or the like, the cap 28 is removed and the tube 27 connected with the usual beer dispensing apparatus. The caps 29 are then removed and the inlet and discharge pipes 18 and 20 connected with a suitable source of cooling liquid including a circulating pump not shown. As the cooling fluid enters the inlet pipe 18, said fluid will flow downwardly through the branch pipes 19 on opposite sides of the partition 12 and within the compartment 7 on one side of the inner receptacle and then transversely across the bottom of said inner receptacle and upwardly within the compartment 7 on the other side of the inner receptacle where it will be discharged through the branch pipes 21, as will be readily understood. During the initial flow of the cooling liquid, a portion of the liquid will be intercepted by the troughs 26 and directed trans-

versely through the cooling tubes 23 and thence out through the branch pipes 21 so that the moment the cooling fluid is introduced within the compartment 7 not only will the exterior of the inner receptacle be thoroughly cooled but also the beer within said receptacle, thereby permitting the serving of cool beer as soon as the keg is tapped. It will, of course, be understood that after the initial flow of cooling fluid has been intercepted by the troughs 26, a further or continued flow of liquid will fill the compartment 7 and said fluid will circulate around the inner receptacle and transversely through the beer until the supply of cooling medium to the keg is cut off. If desired, the caps 29 may be omitted but it is preferred to use the same in order to prevent the entrance of dirt and other foreign matter within the intermediate compartment. In some cases, the caps 29 may be used for confining a cooling medium within the compartment 7 during transportation of the keg and if it is desired to maintain the contents of the inner receptacle in a heated condition during transportation of the keg, the compartment 7 may be used to accommodate a suitable heating medium. It will be noted that the outer ends of the inlet and discharge pipes 18 and 20 as well as the tube 27 are disposed entirely within the lines of the chime 17 of the barrel head so as not to offer any projecting parts when rolling or otherwise transporting the keg, and inasmuch as the fins 12 and 15 and ends of the troughs 26 bear against the inner wall of the outer receptacle or barrel, a strong construction is produced capable of sustaining very rough usage without denting or otherwise damaging the barrel.

While the keg is especially designed for transporting and dispensing beer, it will, of course, be understood that said keg may be used for transporting any other desired beverage or liquid.

It will, furthermore, be understood that the kegs may be made in different sizes and shapes and constructed of any suitable material without departing from the spirit of the invention.

Having thus described the invention, what is claimed as new is:

1. A liquid cooled container comprising inner and outer receptacles having top, bottom and side walls spaced apart to form an intermediate cooling compartment, cooling tubes extending transversely through the inner receptacle and communicating with said intermediate compartment, a partition carried by the inner receptacle and extending transversely across the top and bottom thereof and vertically along the sides of said inner receptacle and engaging the outer receptacle for directing the flow of liquid in a vertical path around the inner receptacle and across the bottom thereof, and liquid inlet and discharge pipes communicating with the intermediate compartment at opposite sides of the container and on opposite sides of said partition.

2. A liquid cooled container comprising inner and outer receptacles spaced apart to form an intermediate cooling compartment, a partition secured to the inner receptacle and extending laterally across the top and bottom thereof and vertically along the sides of said inner receptacle and engaging the outer receptacle for directing the flow of fluid in a vertical path around the inner receptacle, and beneath the bottom thereof, cooling tubes extending transversely through the inner receptacle and provided with terminal liquid directing troughs bearing against the inner receptacle, and fluid inlet and discharge pipes com-

communicating with said intermediate compartment on opposite sides of said container.

3. A liquid cooled container comprising inner and outer receptacles spaced apart to form an intermediate liquid cooling compartment, the inner receptacle being provided with a bung and means for attachment to a dispensing apparatus, partitions secured to the inner receptacle and engaging the outer receptacle for directing the flow of fluid downwardly on one side of the inner receptacle and across the bottom thereof and thence upwardly on the other side of the inner receptacle, cooling tubes extending transversely through the inner receptacle and provided with terminal liquid directing troughs bearing against the inner wall of the outer receptacle, and fluid inlet and discharge pipes disposed on opposite sides of the container and having diverging terminals communicating with the intermediate compartment on opposite sides of the adjacent partition.

4. A liquid cooled container comprising inner and outer receptacles spaced apart to form an intermediate cooling compartment, a lateral partition secured to the inner receptacle and extending transversely across the top and bottom thereof and vertically along the sides of said inner receptacle, an auxiliary partition intersecting the first-mentioned partition and terminating at the bottom of the inner receptacle, cooling tubes extending transversely through the inner receptacle, means carried by the inner receptacle and disposed at the intersection of said partitions for connecting the inner receptacle with a dispensing apparatus, and fluid inlet and discharge pipes disposed on opposite sides of the container and having diverging terminals communicating with the intermediate compartment on opposite sides of the first-mentioned partition.

5. A liquid cooled container comprising an inner receptacle having a bung and provided with means for attachment to a dispensing apparatus, a sectional outer receptacle spaced from the inner receptacle to form an intermediate cooling compartment, intersecting partitions secured to the inner receptacle and bearing against the inner wall of the sections comprising the outer receptacle, one of said partitions extending across the bottom of the inner receptacle and the other terminating flush with said bottom, cooling tubes extending transversely through the inner receptacle, liquid directing troughs carried by the ends of the cooling tubes and disposed within the cooling compartment, and fluid inlet and discharge pipes disposed on opposite sides of the container and having diverging terminals communicating with the cooling compartment on opposite sides of the adjacent partition.

6. A liquid cooled container comprising inner and outer receptacles having top, bottom and side walls spaced apart to form a continuous intermediate cooling compartment, fluid inlet and discharge pipes disposed on opposite sides of the container and communicating with said compartment, and cooling tubes extending transversely through the inner receptacle and each having one end thereof provided with intersecting transverse and longitudinal slits, the metal at said slits being bent laterally on opposite sides of the tubes to form concavo-convex liquid directing troughs dis-

posed within the intermediate compartment and engaging the inner walls of the outer receptacle.

5. A liquid cooled container comprising inner and outer receptacles spaced apart to form an intermediate cooling compartment, supporting feet depending from the bottom of the inner receptacle and resting on the bottom of the outer receptacle, intersecting partitions carried by the inner receptacle, certain of said partitions extending across the bottom of the inner receptacle between the supporting feet and other of said partitions terminating flush with the bottom of said inner receptacle, cooling tubes extending transversely through the inner receptacle, and fluid inlet and discharge pipes disposed on opposite sides of the container and having diverging terminals communicating with the intermediate compartment on opposite sides of the adjacent partition.

10. A liquid cooled container comprising an inner metallic receptacle, an outer metallic receptacle spaced from the inner receptacle to form an intermediate cooling compartment, said outer receptacle being formed in sections each provided with a head having an inclined chime, intersecting partitions carried by the inner receptacle and bearing against the inner wall of the outer receptacle, certain of said partitions extending around the entire outer circumference of the inner receptacle and other partitions terminating flush with the bottom of the inner receptacle, converging fluid inlet and discharge pipes disposed on opposite sides of the container and extending through the inclined chimes of the outer receptacle and provided with diverging branch pipes discharging on opposite sides of the adjacent partition, cooling pipes extending transversely through the inner receptacle and liquid directing troughs arranged at the opposite ends of the cooling pipes and having their inner edges bearing against the outer face of the inner receptacle and their outer edges bearing against the inner face of the outer receptacle.

15. A liquid cooled container having inner and outer receptacles having top, bottom and side walls spaced apart to form an intermediate compartment for the circulation of a cooling medium to cool the contents of the inner receptacle, vertical and horizontal partitions fixed between said receptacles for directing the cooling medium about said inner receptacle, said inner receptacle having conduits extending completely therethrough from one side thereof to the other for conducting the said cooling medium through the said inner receptacle to thereby bring the contents of said inner receptacle into heat exchanging relation, and said conduits being completely sealed against direct contact of said medium and said contents.
